CLAIM

The ornamental design for a bell, as shown and described.

DESCRIPTIONFIG. 1 is a perspective view of a bell showing my new design;
FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The bell of my design provides a hanging decoration hung on a Christmas tree, and also hanging indoors as a decorative item.
